United States Patent Office.

E. C. GORDON, OF SEVASTOPOL, INDIANA.

Letters Patent No. 65,209, dated May 28, 1867.

FENCES.

The Schedule referred to in these Letters Patent and making part of the same.

TO ALL WHOM IT MAY CONCERN:

Be it known that I, E. C. GORDON, of Sevastopol, in the county of Kosciusko, and in the State of Indiana, have invented certain new and useful Improvements in "Fences," and do hereby declare that the following is a full, clear, and exact description thereof, reference being had to the accompanying drawings, and to the letters of reference marked thereon, making a part of this specification.

In the annexed drawings, A A represent a series of the sections composing the fence. The sections are formed of four or more horizontal slats *a a a*, connected at their ends to the uprights *d d*, and braced by the diagonal slat *c* in the centre. These sections may be formed together for a portable fence, attached to the posts in the usual way. This fence is intended more particularly to be a zigzag or "worm" fence, and is constructed without the use of the fence posts or post-holes. B represents the anchor which secures the fence to the ground. This anchor is composed of a piece of wood, stone, or other suitable material having a wire passed under or through it of a length sufficient to be connected to the fence. This anchor is inserted into the ground of a depth suitable to make a firm support, with the two ends of the wire projecting upwards. The sections A A are then set upon the earth with their two inner ends above the anchors, when the wire is passed through the uprights *d d*, and twisted or otherwise secured on the opposite side, (see *x x*, fig. 1.) It will be seen that the outer faces of the uprights of each section are slightly bevelled, so that when connected by means of the anchor they assist each other in supporting the fence.

Having thus fully described my invention, what I claim as new, and desire to secure by Letters Patent, is—

Supporting and connecting the sections A A, as constructed, by means of the anchor B, in the manner herein specified and for the purposes set forth.

In testimony that I claim the foregoing I have hereunto set my hand and seal this second day of April, 1867.
